HEATING DEVICE FOR RAILROAD RAILS
AND SWITCHESWilliam Guenst, Philadelphia, Pa., assignor of
one-half to Ernst L. Ruby, Jenkintown, Pa.

Application July 30, 1930, Serial No. 471,736

2 Claims. (Cl. 219—19)

This invention relates to improvements in heaters for railroad rails and switches.

An object of the invention is to provide a heater with an electrically heated heat conducting part beneath and in contact with the bottom of a rail.

Another object is to provide a heat conducting part beneath and in contact with a track rail and extending therefrom to a position beneath a switch rail which is movably supported adjacent to the track rail.

Another object is to provide a heater located beneath a rail and having a housing extending downwardly therefrom and containing an electric heating element.

Another object is to provide a novel means for holding the frame of the heater and a rail together.

Another object is to provide a heating element of novel construction and a novel means for supporting the element beneath the rail.

The invention consists of the elements and the combinations of them hereinafter described and claimed.

25 In the accompanying drawings, illustrating the invention,

Figure 1 is a side view of a railroad track rail adjacent to a switch rail, showing my improved heater applied to the base of the track rail.

30 Figure 2 is a transverse section through the track rail and the adjacent switch rail, showing the heater applied to the track rail and extending beneath the switch rail.

Figure 3 is a vertical section through the rails and the heater, on line 3—3 of Fig. 1.

Figure 4 is a bottom view of rails and the heater, a part of the heater being broken away.

Referring to the drawings, 2 designates a fixed main or track rail and 4 a switch rail which is 40 movable toward and from the main rail.

My improved heater is secured to the main rail 2 and the frame 5 of the heater is formed of a metal casting and comprises a top wall or plate 6 and a housing 7 extending downwardly therefrom and having an open bottom.

One side of the top wall 6 is fitted against the bottom surface of the track rail 2 in contact therewith, and the opposite side of the wall extends beneath the movable switch rail 4 and 50 beneath the space between the rails 2 and 4.

The wall 6 is provided with upwardly extending lugs 8 and 9 adjacent to the respective sides of the base 10 of the track rail 2 for the purpose of engaging the same and preventing displacement of the frame 5 transversely of the rail;

and the rail 2 and frame 5 are secured or held together by means of a spring clip 11 which embraces one side of the rail base 10 and one side of the wall 6, and clamps them together. The clip 11 is provided with an arm 12 which engages the top of the rail base 10 and an arm 13 which engages the bottom of the wall 6; and the free end of the arm 13 is provided with an upwardly projecting lug 14 which enters a slot 15 in the wall 6 and is adapted to engage a shoulder 65 formed by one side wall of the slot and hold the clip in place.

Before the spring clip 11 is applied to the wall 6 and the rail base 10, the space between the arms 12 and 13 of the clip is somewhat less than that shown in Fig. 3, so that when the clip is applied the arms 12 and 13 will be sprung apart, and thereafter firmly clamp the wall 6 or heater frame and the rail 2 together as the clip tends to resume the normal condition from which it was sprung.

The slot 15 extends parallel with the rail 2 and the length of the slot is much greater than the width of the clip 11, thereby permitting the clip to be adjusted or applied to the rail 2 and frame 5 in different positions of adjustment longitudinally of the rail with respect to the frame 5 to avoid any obstructions which might be present and which might otherwise interfere with placing the heater in a desired position with respect to the rail.

Within the upper portion of the housing 7 is an electric heating element 16 which is clamped against the bottom surface of the wall 6 by a plate 17 beneath the element 16, and a bolt 18 which extends through the plate 17 and the wall 6, as clearly shown in Fig. 3.

The open bottom of the housing 7 is closed by a removable heat insulating plate 19 which is detachably secured by means of screws 20 to bosses 21 which project downwardly from the clamping plate 17. By removing the plate 19 access may be readily had to the interior of the housing.

The heating element 16 is annular in form and it extends around the bolt 18 and it may be of any suitable construction. Preferably it comprises a ribbon resistance manifold 22 contained within a suitable casing 23 of insulating material and having its ends connected to terminals 24 projecting from the casing 23 and connected to electric current conductors or wires 25 which are connected to terminal portions 26 which extend through a housing member 27 projecting from the central portion of the wall 28 of the

heater frame 5. This housing member 27 extends outwardly from within a hole or opening in the wall 28, the inner surface of which is engaged by an outwardly extending flange 29 on the inner end of the member 27. The outer end portion of the member 27 is exteriorly screw-threaded and a clamping nut or ring 30 is screwed onto the same. Surrounding the housing member 27 between the wall 28 and the nut 30 is a series of collars 31 each of which is provided with an outwardly-extending, annular heat radiating flange 32 for a purpose presently appearing. The member 27 and the collars 31 thereon are secured together and to the heater frame 5 by the nut 30 which, when tightened, clamps the frame wall 28 and collars 31 between the housing member flange 29 and the nut.

The outer end of the housing member 27 is closed by a wall 33 formed integral therewith and the terminal portions 26 of the electric current conductors or wires 25 extend through and outwardly beyond the wall 33. These terminal portions or members 26 are rigidly connected to the wall 33 and they are electrically insulated therefrom and from each other, and the outer end portions thereof are provided with suitable clamping nuts 34 by means of which current conducting wires 35 are detachably connected thereto.

The outer end portions of the terminal members 26 and the end portions of the wires 35 connected thereto are enclosed within a hollow head 36, one end of which is internally threaded and screwed onto the housing 27. The other end of the head 36 terminates in a nipple or tubular portion 37 which is surrounded by and connected to a flexible tube or conduit 38 of rubber or other suitable material. The tube 38 is held in place upon the nipple 37 by a suitable clamping collar 39 which surrounds the tube and the nipple. The wires 35 extend through the tube 38 and into the hollow head 36 and they lead from a suitable source of electric current protected by the tube which may be of any desired length to meet the particular conditions where the heater is installed.

It will now be understood that when electric current is supplied to the heating element 16 through the wires 35 and 25, the element 16 will

heat the wall 6 which will transmit the heat to the rail 2 by conduction.

When the heater is in operation the wall 28 of the heater frame will be heated to some extent and the object of providing the flanges 39 is to radiate and dissipate the heat for the purpose of keeping the hose or conduit 38 and the wires 35 therein cool.

My improved heating device may be employed on railroad rails in any selected place where it is desired to heat the same for any purpose. It is particularly adapted for use, however, in connection with switches for the purpose of preventing the accumulation of snow and ice in and around the same from interfering with the proper operation thereof during cold and stormy weather; and when it is so employed it not only heats the main or track rail 2 by conduction but it also heats the adjacent switch rail 4 by radiation, and the heat ascending from the heater through the space between the rails 2 and 4 serves to prevent the accumulation of ice and snow therein.

I claim as my invention,

1. In a heating device for railroad rails, a frame having a wall adapted to fit against the bottom of a rail and provided with a shoulder, a heating element supported beneath and in close proximity to said wall, and a spring clip embracing a part of said wall and adapted to embrace a part of the rail base to hold said wall in contact with the rail base, said clip having a projecting lug adapted to engage said shoulder to retain the clip in place.

2. In a heating device for railroad rails, a frame having a wall adapted to fit against the bottom of a rail and provided with a shoulder and upwardly projecting lugs adapted to engage the respective sides of the rail base, a heating element supported beneath and in close proximity to said wall, and a spring clip embracing a part of said wall and adapted to embrace a part of the rail base to hold said wall in contact with the rail base, said clip having a projecting lug adapted to engage said shoulder to retain the clip in place.

WILLIAM GUENST.
